FIG.3.

FIG.4.

To all whom it may concern:

Be it known that I, Eric W. Nagel, a citizen of the United States, residing at 840 Valencia, resident of St. Louis and State of Missouri, have invented a new, original, and ornamental Design for a Top and Backsplasher Unit for Gas or Electric Range, of which the following is a specification, reference being had to the accompanying drawing, forming a part hereof.

Figure 1 is a fragmentary view in perspective of a top and backsplasher unit for gas or electric range showing my new design;

Figure 2 is a fragmentary top plan view thereof;

Figure 3 is a fragmentary view in front elevation thereof; and

Figure 4 is an end view thereof.

The dominant features of my design reside in the portions shown in full lines.

I claim:

The ornamental design for a top and backsplasher unit for gas or electric range, substantially as shown.
